Design for Type

Patented Sep. 8. 1851.

§ 2

Canon Copperplate Script.

Patent Office, June, 1851.

This is the third size of Copperplate Script, designed to fill a Macaque, or long folio, by the Printers, and challenges admiration for its perfect artistic beauty.

Des. 940

George Bruce, of New York, N. Y.
Letters Patent No. 940. Dated Sept. 8th 1857.

The schedule referred to in these Letters Patent and making part of the same -

To all whom it may concern,

Be it known that J. George Bruce of
the City & County of New York, in the State of New York, typewriter
founder, have invented or produced a new set of printing types
for letter-press printing, of a new and original design, which I
describe as follows, reference being had to the annexed impress-
ion thereof,

It is of the kind usually called Script & of
the size usually called Canon, but, it differs from every other
Script type in shape, size, proportion & in the auxiliary flourishes

D

Des. 940

which constitutes a part of the set.

I call this new type Common Copperplate Script

& I claim the design of the said type as described & shown
herin
